UNITED STATES PATENT OFFICE.

CLAUS E. PETERSON, OF WORCESTER, MASSACHUSETTS.

PIANO-PLAYER.

1,195,265.

Specification of Letters Patent. Patented Aug. 22, 1916.

Application filed May 5, 1911. Serial No. 625,182.

To all whom it may concern:

Be it known that I, CLAUS E. PETERSON, a citizen of the United States, residing at Worcester, in the county of Worcester and 5 Commonwealth of Massachusetts, have invented a new and useful Improvement in Piano-Players, of which the following is a specification, accompanied by drawings, forming a part of the same.

10 My present invention relates to that class of piano players by which the tone producing mechanisms of a piano are actuated by a pneumatic mechanism and controlled by a perforated music sheet traveling over the 15 ducts of a tracker bar.

The objects of my invention are to simplify the construction and increase the efficiency of instruments of this class, and enable a greater range of expression and accuracy of operation to be secured, and I accomplish these objects by the construction and arrangement of parts as hereinafter described and set forth in the annexed claims.

Referring to the accompanying drawings, 25 Figure 1 is a front view showing portions of a piano and of my improved player mechanism. Fig. 2 is a front view of a portion of the pneumatic action on a larger scale, partly shown in section. Fig. 3 is a 30 top view. Fig. 4 is a vertical sectional view on the plane of the broken line 4—4, Fig. 3. Fig. 5 is a front view of a portion of the pneumatic mechanism. Fig. 6 is a sectional view on the plane of the broken line 6—6, 35 Fig. 2. Fig. 7 is a central vertical sectional view of one of the expression boxes. Fig. 8 is a vertical sectional view of the same on the plane of the broken line 8—8, Fig. 7. Fig. 9 is a vertical sectional view through 40 the secondary expression box. Fig. 10 is a vertical sectional view of the regulating box 64. Fig. 11 is a detached sectional view of the primary pneumatic. Fig. 12 is a perspective view of the valve seat and cage for 45 the secondary valve.

Similar reference characters refer to similar parts in the different figures.

Referring to the drawings, 1 denotes a portion of the casing of a piano, comprising 50 a fall board 2 by which the key board is covered and a dust board 3. The tracker bar 4 is represented in Fig. 1 for the purpose of showing its relation to the other parts of the piano and to the player mechanism, the several ducts 5 of the tracker bar

being connected in the usual manner with the primary pneumatics by means of rubber tubes, three of which are shown at 6, Fig. 1.

It will be understood that the usual means of supporting and moving a perforated roll across the ducts 5 of the tracker bar are to be employed, and that exhaust means for removing the air from the pneumatic mechanism and actuated by pedals 65 7, 7 are to be employed in connection with my music roll actuating means, but as these parts are in common use and familiar to those conversant with this class of mechanisms, they have been omitted from the 70 drawings and description.

By means of the pedals 7 and suitable exhaust bellows or feeders operated thereby, air is exhausted from a wind chest 8 connected by suitable passages with the wind 75 trunks 9, 10 and 11, placed, in the present instance, for convenience of illustration beneath the key bed of the piano, but adapted to be located in any desired part of the piano casing, such, for example, as the space 80 immediately behind the fall board 2 and above the keys. Each of the wind trunks 9, 10 and 11 contains two longitudinal chambers 12 and 13, Fig. 4. The trunks are constructed of two parallel horizontal sheet 85 metal plates, one forming a bottom 14 and the other forming a top 15 for the chambers 12 and 13. The bottom and top 14 and 15 are spaced by three longitudinal bars 16, 17 and 18, to which the top and bottom are attached by screws. The top plate 15 extends over the bar 18 and is attached by screws to the internal flanges 19 of a series of ferrules 20 each having at its bottom end an exterior flange 21, which is attached by 90 screws to the upper or stationary leaf 22 of a motor bellows 23 provided with a hinged or movable leaf 24, to the end of which I connect a striker rod 25, suitably connected in a manner common to instruments of this 95 class to the tone producing mechanism of the piano.

Each of the motor bellows 23 communicates with the chamber 13 by a valve controlled air passage which extends through 105 an opening 26, ferrule 20, opening 27, channel 28 and an opening 29 which is normally closed by a valve 30. The channel 28 is enclosed in a cover 31 attached to the top plate 15 and is provided with an opening 32 to the 110

outside air. The valve 30 normally rests upon a valve seat 33 which is inserted in the opening 29 in the form of an eyelet, which is flanged or turned over upon the under side of the plate 15. Integral with the valve seat 33 and extending upwardly into the air channel 28 are the upturned spurs 34, which form a cage for the valve 30. The valve 30 is provided with a valve stem 35 which extends downwardly through an opening 36 in the bottom plate 14 in close proximity to a washer 37 carried upon a flexible diaphragm or pneumatic 38, having its edges clamped between the bottom plate 14 and the flanged edge of a cup 39. The space between the cup 39 and pneumatic 38 forms an air chamber 40, connected with the chamber 41 by tubes 42 and 43 united by a coupling 44. The chamber 41 is inclosed in an inverted cup 45, having a radial flange 46 from the edge of which depends a concentric flange 47 inclosing a disk 48.

The top of the inverted cup 45 is provided with an opening 49 in alignment with a similar opening 50 in the disk 48. The opening 49 communicates with the outside air and is normally closed by a valve 51. The opening 50 communicates, through an enlarged opening 52 in the top plate 15, with the longitudinal chamber 12. The opening 50 is controlled by a valve 53 connected with the valve 51 by a valve stem 54, which extends downwardly through an opening 55 into the bottom plate 14 in close proximity to a washer 56 carried upon a flexible diaphragm or pneumatic 57, having its edges clamped between the bottom plate 14 and the flanged edge of a cup 58. The space between the cup 58 and the diaphragm 57 forms an air chamber 59, connected through the tube 60 with one of the ducts 5 in the tracker bar 4 by means of one of the rubber tubes 6.

Each of the longitudinal chambers 12 is connected with a vertical chamber 61, and each of the longitudinal chambers 13 is connected with a separate vertical chamber 62. The chamber 61 is connected by a pipe 63 with a regulating box 64, shown in sectional view in Fig. 10, and the regulating box 64 is connected with the wind chest 8 by a pipe 65. Between the pipes 63 and 65 and inclosed in the regulating box 64 is a valve controlled passage 66, Fig. 10. The action of a valve 67 closing said passage is controlled by a bellows 68 normally held expanded by the tension of a spring 69. When the air tension in the chamber 61 and connected chamber 70 in the regulating box 64 becomes greater than the tension of the spring 69 the bellows 68 collapses and closes the passage 66. By this means a uniform air tension is maintained throughout the longitudinal chambers 12, thereby causing all the primary valves which are actuated by the pneumatics 57 to be operated under an air ten-

sion which is not only uniform but is limited in amount by the tension of the spring 69.

The vertical chamber 62 which has a communication with each of the longitudinal chambers 13 is connected by a pipe 71 with a regulating box 72, shown in sectional view in Figs. 7 and 8, the section shown in Fig. 8 being on a plane at right angles to that shown in Fig. 7. The regulating box 72 is connected by a pipe 73 with the wind chest 8, and between the pipes 71 and 73 is a valve controlled air passage 74 arranged to be closed by a valve 75, having its valve stem 76 connected by a link 77 with a bell crank lever 78. The longitudinal chambers 13 are connected at their opposite ends with a vertical chamber 79 connected by a pipe 80 with a valve cut off box 81, shown in sectional view in Fig. 9, and communicating through an opening 82 with the wind chest 8. Between the opening 82 and the pipe 80 is a valve controlled passage 83 closed by a cut-off valve 84. The valve 84 is connected by a stem 85 with a bell crank lever 86. The bell crank levers 78 and 86 are coupled together by the links 87 and 88 and a two armed lever 89, provided with a handle 90 by which the valves 75 and 84 may be moved in unison. The valve 84 is considerably longer than the air passage 83 to allow considerable movement of the valve 84 before the passage 83 is opened. The sliding movement of the valve 84 is also greater than that of the valve 75 due to the difference in leverage between the bell cranks 78 and 86. By this arrangement the valve 75 and the valve 84 are operated by the handle 90 and when the bell cranks 78 and 86 are rocked to open the valves 75 and 84 the valve 75 opens in advance of the opening of the valve 84. When the valves 75 and 84 are closed the valve 84 closes in advance of the closing of the valve 75.

By the above described arrangement of the connection between the valves 75 and 84 the air passage 74 may be varied in extent in order to vary the air tension in the longitudinal chambers 13 without opening the valve 84. When the valve 75 is nearly opened the valve 84 begins to open, so that the continued movement of the valves 75 and 84 will then increase the openings in both passages 74 and 83 and rapidly increase the air tension in the longitudinal chambers 13, thereby enabling an explosive note to be sounded.

I claim:

1. In a piano player, a horizontal wind trunk, consisting of longitudinal bars and plates attached to said bars inclosing separate vacuum chambers, means for exhausting the air from said chambers, and two independent means of communication between one of said vacuum chambers and said air exhausting means.

2. In a piano player, a series of horizontal wind trunks consisting of longitudinal bars and plates attached to said bars inclosing parallel separate vacuum chambers, with primary, secondary and motor pneumatics attached to the outside of said plates and communicating with said chambers.
3. In a piano player, a series of horizontal wind trunks each consisting of longitudinal bars and plates attached to said bars inclosing two separate vacuum chambers, a vertical chamber communicating with one end of one of said chambers in each of said trunks, a vertical chamber communicating with the opposite ends of said vacuum chambers, means for exhausting the air from said vertical chambers and independent valve controlled passages connecting said vertical chambers with said exhausting means.
4. In a piano player, a wind trunk containing a vacuum chamber, a series of motor bellows having valve controlled communication with said vacuum chamber, means for exhausting air from said vacuum chamber, and independent valve controlled passages between the opposite ends of said vacuum chamber and said air exhausting mechanism.
5. In a piano player, a horizontal longitudinal vacuum chamber having an opening in its upper wall, an inverted cup having a flanged edge, a disk fitting in and held by said flanged edge covering said opening and forming a valve seat, an opening in said inverted cup leading to the outer air and having a valve seat, valves for said valve seats having a common valve stem, and means for actuating said valve stem to alternately open and close said valves.
6. In a piano player, a horizontal longitudinal casing inclosing a vacuum chamber, said casing consisting of parallel spacing bars and metal plates attached thereto to form the bottom and top of said chamber, with said top plate overhanging said casing, a ferrule attached to the overhanging edge of said top plate, a motor bellows attached to said ferrule, and a valve controlled communication through the ferrule between said bellows and said vacuum chamber.
7. In a piano player, primary and secondary pneumatics, a casing inclosing longitudinal chambers for the primary and secondary pneumatic, a motor bellows placed beneath said casing and transversely thereto, a ferrule connecting one end of said motor bellows with said casing, and an air passage passing through said ferrule and connecting
- said motor bellows and said vacuum chamber.
8. In a piano player, a casing inclosing a vacuum chamber, a valve opening in the wall of said chamber, a valve covering said opening, and spaced guides surrounding the valve to maintain it in proper position relatively to said opening.
9. In a piano player, a casing consisting of spacing bars and top and bottom plates inclosing longitudinal parallel vacuum chambers, a series of primary pneumatics connected with one of said vacuum chambers, means for maintaining a uniform vacuum in said chamber, a series of secondary pneumatics connected with the other of said vacuum chambers, and means for varying the vacuum in said second chamber.
10. In a piano player, a horizontal longitudinal casing inclosing a vacuum chamber, said casing consisting of parallel spacing bars and metal plates attached thereto, to form the bottom and top of said chamber, with said top plate provided with an opening, a valve closing said opening, a metal cover for said valve attached to said top plate and having an opening above said valve to the outside air arranged to be closed by said valve, means for actuating said valve to alternately open and close said openings, a motor bellows supported directly beneath said vacuum chamber, and a passage between said motor bellows to the chamber inclosed by said valve cover.
11. In a piano player, a longitudinal vacuum chamber, means for exhausting air therefrom, independent passages for connecting the opposite ends of said chamber with the air exhausting mechanism, valves for controlling the movement of air through each of said passages, and means for operating said valves at different rates of speed.
12. In a piano player, a longitudinal vacuum chamber, means for exhausting air therefrom, independent passages for connecting the opposite ends of said chamber with said air exhausting mechanism, valves for controlling the flow of air through said passages, and means for operating said valves, whereby one of said passages will be opened in advance of the other.

Dated this fourth day of May, 1911.

CLAUS E. PETERSON.
